GUN PERFORATOR

Filed March 4, 1942

UNITED STATES PATENT OFFICE

2,331,057

GUN PERFORATOR

Lloyd Spencer, Los Angeles, Calif., assignor to
 Lane-Wells Company, Los Angeles, Calif., a corporation of Delaware

Application March 4, 1942, Serial No. 433,257

20 Claims. (Cl. 164—0.5)

My invention relates to gun perforators; that is, to devices which are lowered into well casing and caused to fire bullets through the casing to permit inflow of fluid. Among the objects of my invention are:

First, to provide a gun perforator which comprises a plurality of separate gun units which are adapted to be stacked and secured end to end;

Second, to provide a sectional multiple unit gun perforator wherein each gun unit is complete in itself in that it comprises a gun bore and cartridge socket which may be loaded before being assembled with other gun units;

Third, to provide a sectional gun perforator in which the gun sections or units are particularly simple and economical of manufacture, and any one of the gun units may be readily removed and replaced in the event it should become damaged;

Fourth, to provide a gun perforator in which the axial length of each gun unit is minimized so that a maximum number of units may be incorporated in a gun of given length and weight;

Fifth, to provide a gun perforator which may be initially ignited electrically or otherwise and is so arranged that each gun unit as it fires ignites the succeeding gun unit, so that other than initiating the discharge of the uppermost gun unit no electrical or mechanical means is required to insure discharge of the succeeding gun units;

Sixth, to provide a gun perforator in which the axes of the gun bores of the several gun units may define compositely a spiral, that is, the muzzle ends of the gun units define spiral paths so as to distribute the gun perforations uniformly around the walls of the casing;

Seventh, to provide a gun perforator wherein a time-delay is introduced between the ignition of each gun unit, so that the gun units fire in sequence to reduce the pressure surge such as would be created were the gun units fired simultaneously; and

Eighth, to provide a gun perforator which incorporates some of the advantages of the gun perforator disclosed in my preceding patent, No. 2,266,343, issued December 16, 1941.

With the above and other objects in view, as may appear hereinafter, reference is directed to the accompanying drawing, in which:

Figure 1 is an elevational view of my gun perforator as it appears when assembled;

Figure 2 is a top or plan view of one of the gun units, indicating by dotted lines the position of the succeeding gun units below;

Figure 3 is a fragmentary longitudinal sectional view taken substantially through 3—3 of Figure 2; and

Figure 4 is a transverse sectional view of the breech plug before assembly.

My gun perforator includes a plurality of gun units. Each gun unit 1 is in the form of a cylindrical disk or block which is divided diametrically into a breech portion 2 and a barrel portion 3 which are therefore semi-cylindrical. The breech portion 2 has greater axial length than the barrel portion and therefore extends above and below the upper and lower sides of the barrel portion to form steps or shoulders 4. The upper and lower corners of the barrel portions which are extended from the steps 4 are provided with axially directed ribs 5 having faces which are parallel to the steps 4. Complementary recesses 6 are provided in the corners of the breech portion 2. The breech and barrel portions are so proportioned that the breech end of one gun unit is adapted to fit upon the barrel portion of the adjacent gun unit, as shown in Figures 1 and 3, with the steps, ribs and recesses interlocking. Furthermore, the steps and ribs formed on the lower side of each gun unit are offset arcuately a predetermined amount from the upper set of shoulders, steps and recesses, as indicated by broken lines in Figure 2. Thus, when the gun units are stacked upon each other in proper sequence, corresponding points on the peripheries of the gun units define longitudinal spirals or helices.

The barrel 3 is provided with a diametrically extending gun bore 7, preferably centered between the two planes of the upper and lower steps 4, that is, if the upper and lower steps are displaced relatively 10° the axis of the gun bore is preferably approximately 85° with respect to each of the steps.

Each gun bore 7 extends into the breech portion 2 and is intersected by a vertically extending cartridge bore or socket 8, which extends past the gun bore but is open only to one axial end of the breech portion. Each cartridge bore 8 is preferably slightly larger in diameter than the gun bore and its axis is offset from the axis of its gun bore arcuately an amount equal to the arcuate displacement of the gun unit above; that is, if the displacement is 10° the axis of the cartridge bore or socket is offset from its corresponding gun bore 10°. As a consequence, the cartridge bore of each gun unit aligns vertically with the gun bore of the unit above.

Each gun bore 7 receives a bullet 9 which is positioned at the inner end thereof. The outer

end of each gun bore is provided with a rudimentary counterbore and receives a sealing disk 10 which may be of a type more fully described in the Turechek Patent No. 2,216,144 issued October 1, 1940. The cartridge bore 8 receives a cartridge 11 which is for the purposes of this application conventional and comprises a shell of Celluloid or analogous material filled with an explosive.

The upper end of each cartridge bore 8 is provided with a counterbore 12 and the lower side of the gun unit above is provided with a complementary recess 13. The counterbore and recess receive a breech plug 15. A small passage 14 extends in all gun units except the one adjacent the head 24 from the gun bore of the unit above to the recess 13.

The breech plug 15 is in the form of a short cylinder and is provided with a small bore 16 therethrough. The upper end of the bore 16 is preferably enlarged and its upper extremity provided with an internal flange or pressure lip 17. Similarly, the outer periphery of the breech plug 15 is provided adjacent its upper and lower edges with annular channels which define pressure lips 18 and 19. The lower end of the breech plug is provided with a depending pressure skirt 20 which fits into the upper end of the cartridge bore 8. As shown in Figure 4, the pressure lips 18 and 19 are initially formed to extend above and below the normal upper and lower faces of the breech plug, so that when the breech plug is clamped between adjacent gun units the pressure lips are forced downward, but maintains a sealing connection with their respective recess or counterbore. The pressure skirt 20, when fitted within the cartridge bore, bears against the walls of the cartridge bore 8 to seal against internal pressure occasioned by ignition of the explosive cartridge.

On opposite sides of each cartridge bore 8 the breech portion 2 is provided with threaded bolt shank sockets 21 and, similarly, on opposite sides of each gun bore the barrel portion 3 is provided with bolt head sockets 22. Bolts 23 extend through the bolt sockets 22 of one gun unit and into the threaded sockets 21 of the adjacent gun unit, so that the several gun units are bolted together on opposite sides of their respective cartridge bores. The bolts are preferably of the recessed head type.

The uppermost gun unit is secured to a head member 24, the underside of which is provided with a step 4, rib 5 and recess 6 corresponding to those on the gun unit. In addition, the head member is provided with clearance recesses 25 adapted to receive the bolts 23. Also, the head member 24 is provided with a recess 18 complementary to the counterbore 12 of the uppermost gun unit. Above this recess the head member 24 is provided with an ignition fuse socket 26 which receives an ignition fuse 27. The ignition fuse is preferably of the electrically ignited type; for example, it may comprise a match head compound or a small amount of explosive, or both, molded around a resistance wire or ignition wire. The ignition wire (not shown) is preferably connected to a suitable conductor 28. The head member is suitably connected to a cable (not shown) which preferably carries a conductor so that current may be supplied to the ignition fuse.

The lowermost gun unit is covered by a foot member 29 and a blank breech plug 30 is em-

ployed to close the passage 14 of the lowermost gun unit.

Operation of my gun perforator is as follows: The ignition fuse 27 ignites the first cartridge, which discharges its bullet. As soon as the first bullet has passed its passage 14, flame from the uppermost cartridge ignites the cartridge of the succeeding gun unit, and so on until all the gun units are fired. It will be noted that the gun units are ignited in sequence; that is, the bullet from the first gun unit is practically discharged before the second gun unit is ignited. This affords an appreciable time interval between discharge of the gun units so that the casing does not receive the blast from all the gun units simultaneously, but instead the force is distributed in time so that the maximum pressure on the casing is not excessive. Also, by reason of the fact that the gun bores may be arranged spirally, the pressure against the casing is uniformly distributed.

The breech plug bore 16 is preferably large enough to enable the flame from the preceding gun unit to ignite the succeeding cartridge, but small enough to minimize any pressure loss. By reason of the pressure skirt 20 and the pressure lips 17 the force tending to separate the gun units is limited to the pressure exerted on an area equal to the cross section of the cartridge bore. This is a comparatively small area and the force on this area is well within the strength of the two bolts 23.

The breech block 15 may be of such thickness that it tends to space the adjacent gun units a slight distance. In this case the entire force exerted by the tension of the bolts is taken by the breech block; therefore insuring a tight seal at its upper and lower faces. However, by arranging the pressure lips so that they are normally above their corresponding surfaces of the breech plug, adequate sealing is obtained without requiring the breech plug to take the full tension of the bolts.

Various changes and alternate arrangements may be made within the scope of the appended claims, in which it is my intention to claim all novelty inherent in the invention.

I claim:

1. A gun perforator comprising: a plurality of gun units in the form of cylindrical disks having a greater diameter than thickness, said cylindrical disks being stacked axially, each gun unit having a laterally directed gun bore and a longitudinally directed cartridge bore wholly open at one axial end, each cartridge bore being covered by the adjacent gun unit; means for securing said gun units together in a manner to withstand explosive pressures; and means defining passages connecting the cartridge bores of said gun units in series whereby the flame incidental to discharge of one gun unit is propagated to the succeeding gun unit.

2. A gun perforator comprising: a plurality of gun units, each defining a radially directed gun bore and a longitudinally directed cartridge bore intersecting an end of said gun unit to form a cartridge loading opening, each gun unit forming a cover portion adapted to fit over and close the cartridge bore of an adjacent gun unit when said gun units are stacked; each cover portion defining a passage forming at least part of a means of communication between the cartridge bores of said adjacent gun units whereby the flame in one cartridge bore may be propagated to the others.

3. A gun perforator comprising: a plurality of

gun units, each being a short cylindrical section and having a breech portion of major thickness and a barrel portion of minor thickness, said gun units adapted to be stacked with their barrel portions and breech portions staggered; each gun unit having a cartridge socket in its breech portion and a gun bore extending diametrically therefrom through said barrel; and means defining passages between the gun bore of each gun unit and the cartridge socket of the adjacent gun unit whereby the cartridge sockets of the plurality of gun units are connected serially for the propagation of flame incidental to the discharge of said gun units.

4. A gun perforator comprising: a plurality of gun units in the form of cylindrical blocks stacked to form a composite column; said blocks having complementary stepped axial ends restraining said blocks against relative lateral movement, and each block defining a laterally directed gun bore and an axially directed cartridge socket, said cartridge sockets being closed by confronting ends of the adjacent blocks; and means defining passages incorporating said gun bores and connecting said cartridge sockets in sequence, whereby an ignition flame may be propagated throughout said plurality of gun units.

5. A gun perforator comprising: a plurality of gun units in the form of blocks, each having a longitudinally directed cartridge socket wholly open at one axial end and a laterally directed gun bore, said blocks adapted to be stacked in such a manner that the cartridge socket of each gun unit is sandwiched between the gun bore defining portions of adjacent gun units and covered thereby; means for securing said gun units together against explosive pressures that may be generated in said cartridge sockets; and means defining an ignition passage extending between the cartridge sockets of said gun units.

6. A gun perforator comprising: a plurality of gun units, each defining a radially directed gun bore and a longitudinally directed cartridge bore intersecting one end of said gun unit, said gun units adapted to be stacked with the side of one gun unit closing the cartridge bore of the adjacent gun unit; axially directed securing means extending between adjacent gun units on opposite sides of said cartridge bores to hold said gun units in sealing relation; and passage-defining means directly connecting intermediate its ends the gun bore of each gun unit to the cartridge bore of the adjacent gun unit, whereby the cartridge bores are serially connected for the propagation of an ignition flame.

7. A gun perforator comprising: a plurality of gun units, each defining a radially directed gun bore intersecting one side of said gun unit and a longitudinally directed cartridge bore intersecting one end thereof, said gun units adapted to be stacked with the end of one gun unit closing the cartridge bore of the adjacent gun unit; said gun units directed alternately in opposite directions, the gun bore of each being between the cartridge bores of the adjacent gun unit; tie bolt on opposite sides of the gun bore of each gun unit extending therefrom into an adjacent gun unit on opposite sides of the cartridge bore of said adjacent gun unit; and passage-defining means directly connecting the gun bore of each gun unit intermediate its ends to the cartridge bore of the adjacent gun unit, whereby the cartridge bores are serially connected for the propagation of an ignition flame.

8. A gun perforator comprising: a series of gun units, each defining a gun bore and a cartridge bore; and means defining an ignition passage directly connecting the gun bore itself of one gun unit intermediate its ends with the cartridge bore of the adjacent gun unit.

9. A gun perforator comprising: a series of gun units, each defining a gun bore and a cartridge bore; a bullet for each gun bore; a cartridge for each cartridge bore; means defining an ignition passage connecting directly the gun bore of one gun unit between the bullet and muzzle end of said gun bore with the cartridge bore of the adjacent gun unit; and covers sealing the muzzle ends of said gun bores.

10. A gun perforator comprising: a series of gun units, each defining a gun bore and a cartridge bore; means defining an ignition passage directly connecting the gun bore of one gun unit intermediate its ends with the cartridge bore of the adjacent gun unit; and a removable plug having a reduced bore fitting said ignition passage.

11. A gun perforator comprising: a series of gun blocks adapted to be stacked, each gun block defining a laterally directed gun bore and a cartridge chamber communicating therewith; said gun blocks having complementary interlocking elements on each end, the interlocking elements on one end being offset arcuately from those on the other end whereby, when said blocks are stacked, the muzzle ends of said gun bores define helical paths.

12. A gun perforator comprising: a series of gun blocks adapted to be stacked, each defining a laterally directed gun bore, a cartridge bore and an ignition passage leading from the gun bore, said ignition passage adapted to register with the cartridge bore of an adjacent gun block when said blocks are stacked; said gun blocks having complementary interlocking elements on each end, the interlocking elements on one end being offset arcuately from those on the other end whereby, when said blocks are stacked, the muzzle ends of said gun bores define helical paths.

13. A gun perforator comprising: a series of gun blocks adapted to be stacked end to end; each gun bore defining a laterally extending gun bore, a longitudinally extending cartridge bore communicating with its gun bore and intersecting an end of said gun block, and an ignition passage leading directly from the gun bore intermediate its ends and intersecting the opposite end of said gun block, the ignition passage of each gun block adapted to communicate with the cartridge bore of the adjacent gun block.

14. A gun perforator comprising: a series of gun blocks adapted to be stacked end to end; each gun bore defining a laterally extending gun bore, a longitudinally extending cartridge bore communicating with its gun bore and intersecting an end of said gun block, and an ignition passage leading directly from the gun bore intermediate its ends and intersecting the opposite end of said gun block, the ignition passage of each gun block adapted to communicate with the cartridge bore of the adjacent gun block; and breech plugs interposed between said ignition passages and their corresponding cartridge bores, said breech plugs having restricted ignition bores therethrough.

15. A gun perforator as defined in claim 14 wherein said breech plugs include means for confining the pressure area between said gun blocks substantially to the area of said cartridge bores; and tie bolts extending past opposite sides of the gun bore of one gun block and into the adjacent

gun block on opposite sides of its cartridge bore.

16. A gun perforator comprising: a series of gun blocks adapted to be stacked end to end; each gun bore defining a laterally extending gun bore, a longitudinally extending cartridge bore communicating with its gun bore and intersecting an end of said gun block, and an ignition passage leading from the gun bore and intersecting the opposite end of said gun block, the ignition passage of each gun block adapted to communicate with the cartridge bore of the adjacent gun block; said gun blocks having complementary interlocking elements on each end, the interlocking elements on one end being offset arcuately from those on the other end whereby, when said blocks are stacked, the muzzle ends of said gun bores define helical paths.

17. A gun perforator comprising: a series of gun blocks adapted to be stacked end to end; each gun bore defining a laterally extending gun bore, a longitudinally extending cartridge bore communicating with its gun bore and intersecting an end of said gun block, and an ignition passage leading from the gun bore and intersecting the opposite end of said gun block, the ignition passage of each gun block adapted to communicate with the cartridge bore of the adjacent gun block; breech plugs interposed between said ignition passages and their corresponding cartridge bores, said breech plugs having restricted ignition bores therethrough; said gun blocks having complementary interlocking elements on each end, the interlocking elements on one end being offset arcuately from those on the other end whereby, when said blocks are 35

stacked, the muzzle ends of said gun bores define helical paths.

18. A gun perforator as defined in claim 17 wherein said breech plugs include means for confining the pressure area between said gun blocks substantially to the area of said cartridge bores; and tie bolts extending past opposite sides of the gun bore of one gun block and into the adjacent gun block on opposite sides of its cartridge bore.

19. A gun perforator comprising: a gun block having a laterally directed gun bore intersecting a side of said gun block, a longitudinally directed cartridge bore at the inner end of said gun bore intersecting an end of said gun block, and an ignition passage leading directly from said gun bore itself and intersecting the opposite end of said gun block; said gun block adapted to be stacked end to end with other similar gun blocks, the ends of each gun block having complementary interlocking elements arranged so that the gun blocks stack in two sets with cartridge bores in registry with the ignition passage of the adjacent gun block, and the gun bores pointing alternately in opposite directions.

20. A gun perforator construction as defined in claim 19 wherein the interlocking elements on one end of each gun block is offset arcuately with respect to those on the opposite end whereby, upon stacking said gun blocks, the muzzle ends of the gun bores define helical paths; and wherein the axis of each cartridge bore is offset from the axis of its gun bore to align with the ignition passage of the adjacent gun block.

LLOYD SPENCER.
